DESIGN FOR A TEXTILE WOVEN FABRIC

Edward Grant Hayward, Jr., Auburn, R. I.

Application April 26, 1934, Serial No. 51,527

Term of patent 14 years

To all whom it may concern:

Be it known that I, EDWARD GRANT HAYWARD, JR., a citizen of the United States of America, residing in Auburn, county of Providence, State of Rhode Island, have invented a new, original, and ornamental Design for a Textile Woven Fabric, of which the following is a specification, reference being had to the accompanying drawing forming a part thereof.

The figure is a plan view of a textile woven fabric showing my new design.

I claim:

The ornamental design for a textile woven fabric, substantially as shown.

EDWARD GRANT HAYWARD, JR.
